UNITED STATES PATENT OFFICE.

HELEN MELLEN, OF LOS ANGELES, CALIFORNIA.

DESIGN FOR A HOUSE-DRESS.

59,561.

Specification for Design.

Patented Nov. 1, 1921.

Application filed April 18, 1921. Serial No. 462,445. Term of patent 7 years.

To all whom it may concern:

Be it known that I, HELEN MELLEN, a citizen of the United States, residing at Los Angeles, in the county of Los Angeles and State of California, have invented a new, original, and ornamental Design for a House-Dress, of which the following is a specification, reference being had to the accompanying drawing, forming a part thereof.

Fig. 2 is a rear conventional view of the same.

I claim:

The ornamental design for a house dress, as shown.

HELEN MELLEN.
